(57) **CLAIM**

The ornamental design for a food blender, as shown and described.

DESCRIPTION

FIG. 1 is a perspective view of a food blender showing my new design;

FIG. 2 is another perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof; and,

FIG. 9 is an exploded perspective view of the food blender. The attachments shown in broken lines in FIG. 9 depict environmental subject matter and form no part of the claimed design. The remaining broken lines in the figures depict portions of the food blender and form no part of the claimed design.

1 Claim, 9 Drawing Sheets
